UNITED STATES PATENT OFFICE.

FRANK L. SACKETT, OF FREDONIA, NEW YORK.

COAL-SCREEN.

SPECIFICATION forming part of Letters Patent No. 508,345, dated November 7, 1893.

Application filed May 5, 1893. Serial No. 473,062. (No model.)

To all whom it may concern:

Be it known that I, FRANK L. SACKETT, of Fredonia, in the county of Chautauqua and State of New York, have invented a new and useful Improved Coal-Screen, of which the following is a full, clear, and exact description.

This invention relates to improvements in coal screens that are used to screen broken coal for retail purposes, and has for its objects to provide a novel, simple, inexpensive and convenient device of the character indicated, which will afford means to thoroughly screen coal of different grades, and that may be attached to the side of a car or cart, or be inclined against an upright support for use; a further object being, to provide an adjustable and removable hopper for the screen, which will conduce to the efficiency of the screen in cleaning coal of fine grades.

To these ends, my invention consists in the peculiar construction and combination of parts, as are hereinafter described and claimed.

Reference is to be had to the accompanying drawings forming a part of this specification, in which similar letters of reference indicate corresponding parts in both of the figures.

Figure 1 is a perspective view of the improvement complete, in position for service on the side of a car body in part; and Fig. 2 is a longitudinal, sectional view of the screening device, and a cross section of the car body portion.

The coal screen comprises a rectangular frame A, of ordinary form, whereon screen wire fabric B, of a suitable mesh, is secured by any suitable means, a proper length and breadth being provided for these parts to insure effective action for the screen. This part of the device is not claimed as of a new construction.

Upon the upper ends of the side bars on the frame A, two similar stout hooks C, are secured, these having their hook portions projected sufficiently beyond the screen frame to permit them to engage their sharpened points with the car side-board D, or if necessary, with the side of a cart or wagon body, and preferably the projecting hook portions are curved of such a radius as will adapt the hooks to take a firm hold on the edge portion of the car side-board, and permit a vertical

adjustment of the screen frame to regulate its pitch or inclination, as may be desired.

A prop brace E, is a feature of the invention, and consists of a bar of wood or metal of such dimensions as will afford required strength and render the brace effective in use, a sharp point a, being formed upon or secured to one end of the brace to adapt it for a secure engagement with the wooden side wall of a car, coal bin or cart that it may be placed in contact with. At the opposite end of the prop brace E, along one edge, a series of properly spaced notches b, are formed therein, and on the side of the screen frame A, near its lower end, a staple c is inserted, affording a projecting loop through which the notched end portion of the prop brace will slide, and if desired, may be adjusted to engage any one of the notches with the loop of the staple, thereby removably securing the prop brace to the staple and upon the frame A, near its coal delivery end; and it will be seen that by an adjustment for length in the manner specified, the prop brace may be adapted to hold the screen frame and wire fabric on it, inclined at different angles from a horizontal plane, another staple c', being secured at the other end of the frame, which will hold the prop brace folded when not in use.

On the screen frame A, the removable and longitudinally adjustable hopper G, is located, which part is an important feature of the invention, and consists essentially of a rectangular receptacle having two side walls that are held spaced apart and parallel, by the end wall e and bottom board g. Sufficient width is given to the hopper G, to permit it to engage the lower edges of its side walls with the side bars of the frame A, or locate the laterally projected ledges h, that are secured on the side walls upon the frame side bars, as shown in Fig. 1. The side walls of the hopper G are preferably sloped on the top edges, from the end wall e, toward the open end that in use is nearest to the top of the screen frame A. The bottom board g, of the hopper, is made of a less length than that of the hopper side walls, which by the location of the bottom board produces a transverse discharge opening i, in the bottom of the hopper adjacent to the end wall e. Preferably, the inner surface of the end wall

- e, and the upper side of the bottom board g, are protected by sheet metal, (not shown.) If the hopper G, is formed from wooden planking, or boards, the upper edges of the 5 sides and end wall are preferably protected by the metal strips e', that are secured thereon with screws or by other means. Two opposite hooks m (one being shown in Fig. 1) are loosely secured upon the side walls of the 10 hopper G, or upon the ledges h, as may be preferred, and on each side bar of the screen frame A, a row of spaced staples n, are inserted, for the hooks m to engage with, and it will be seen that by changing the hooks 15 from one pair of opposite staples to another pair, the hopper G, may be changed in position on the screen frame, so as to locate it at any desired distance from the top of the screen, or at the top, as shown in Fig. 1.
- 20 When coal of fine grades is to be screened as removed from the car, the hopper G, is preferably secured at the top of the screen frame, and the latter attached to the top edge of the car side-board, as represented in Fig. 25 1, a suitable inclination being given to the screen by an adjustment of the prop brace E. From the position given to the improved device, coal in the car can be shoveled therefrom into the hopper G, from which it will 30 escape in an evenly spread layer upon the screen B, and thus be caused to traverse nearly the entire length of said screen, separating the dust and fine fragments of coal from that which is merchantable.
- 35 In some cases, it may be of advantage to haul the coal in carts or wagons from the car at a railroad station to the coal yard, for subsequent retail distribution, the coal being screened at the yard, which may be effected 40 conveniently with the improved screening device, by attaching the screen frame upon the side or rear end of the cart or wagon body, and then shoveling the coal from the vehicle body into the hopper G, from which it will 45 escape as before explained, thus insuring a complete screening of the coal as the wagon or cart is unloaded.
- When coal is to be screened from the ground 50 the frame and attached screen may be held at a proper angle by using prop brace E, the notched end of which may be adjusted in staple c, which will elevate the end of the screen whereon the staple is placed. Hard

coal of large size or even soft lump coal may be run over this screen by simply removing 55 the hopper.

By the use of the improved device, thorough cleaning of the coal is insured, which does not always result if coal that is pervaded with considerable dust and dirt is screened 60 in the ordinary way, as there is no means to compel the coal handler to throw the coal upon the screen at a proper elevation to effect a complete removal of the waste material from the coal. 65

If the hopper is used to screen coal that lies below it, and which has to be lifted with a shovel and thrown into said receptacle, it may be advantageous should the screen be of considerable length, to adjust the hopper on 70 the frame nearer the lower end than is represented in the drawings, by changing its hooked connection with the frame, so that coal when shoveled and lifted may be more easily thrown into the hopper, which in all 75 cases should be so arranged upon the screen that a sufficient portion of the screen will be traversed by the coal to insure its complete separation from the refuse material.

Having thus described my invention, I 80 claim as new and desire to secure by Letters Patent—

1. The combination, with the coal screen, composed of an oblong frame, A, having the screen proper, B, stretched across it as shown, 85 of the hopper, having an end wall, e, and discharge opening, and whose bottom rests and is adapted to slide on the side bars of the said coal screen, and fastening devices applied as shown, for securing the hopper at 90 different points on the screen frame, as shown and described.

2. The combination, with the oblong, rectangular coal screen A, B, of the adjustable hopper, having a discharge opening at its 95 lower corner and having side ledges which rest and are adapted to slide on the side bars of the screen, and the hooks and staples applied to said hopper and bars for securing the hopper at different points, as shown and described. 100
